Primary Examiner — Lauren R Calve(74) *Attorney, Agent, or Firm* — Merchant & Gould P.C.**CLAIM**

The ornamental design for a valve component, as shown and described.

DESCRIPTION

FIG. 1 is a front isometric view of a valve component;
FIG. 2 is a front view thereof;
FIG. 3 is a rear view thereof;
FIG. 4 is right side view thereof;
FIG. 5 is a left side view thereof;
FIG. 6 is a top view thereof;
FIG. 7 is a bottom view thereof; and,
FIG. 8 is a cross sectional view taken along line **8-8** shown
in FIG. 2.

The short dash-long dash broken lines shown in FIG. 2
represents the plane upon which the cross sectional view is
taken and forms no part of the claimed design. The evenly
spaced broken lines in the drawings represent portions of the
valve component that form no part of the claimed design.
The dot dash broken lines in the drawings represent a
boundary of the claimed design. A non-limiting example
application of the valve component is for use in a hydraulic
valve of a shock absorber.
